US00D879520S

(12) United States Design Patent (10) Patent No.: US D879,520 S
(45) Date of Patent: * Mar. 31, 2020

(54) RETAIL FURNISHINGS GROUP

(71) Applicant: Apple Inc., Cupertino, CA (US)

(72) Inventors: Rebecca M. Cully, Moss Beach, CA (US); Jennifer Ross Wynn, San Francisco, CA (US); Christopher M. Green, Woodside, CA (US); Christopher Daniel Peak, Oakland, CA (US); David Kahl Peschel, San Carlos, CA (US); Stefan Behling, London (GB); James Sherman, London (GB); Vasileios Bakas, London (GB)

(73) Assignee: Apple Inc., Cupertino, CA (US)

() Term: 15 Years

(21) Appl. No.: 29/658,949

(22) Filed: Aug. 3, 2018

Related U.S. Application Data

(63) Continuation of application No. 29/571,098, filed on Jul. 14, 2016, now Pat. No. Des. 824,704, which is a continuation of application No. 29/537,119, filed on Aug. 21, 2015, now Pat. No. Des. 812,771.

(57) CLAIM

The ornamental design for a retail furnishings group, as shown and described.

DESCRIPTION

FIG. 1 is a front perspective view of a retail furnishings group showing the claimed design;

FIG. 2 is a left side view thereof;

FIG. 3 is a right side view thereof;

FIG. 4 is a front view thereof;

FIG. 5 is a rear view thereof; and,

FIG. 6 is a top view thereof.

The dashed broken lines in the figures show portions of the retail furnishings group that form no part of the claimed design.

The dot-dash broken lines in the figures show boundaries that form no part of the claimed design.

1 Claim, 6 Drawing Sheets
